UNITED STATES PATENT OFFICE.

MILTON T. CAMPBELL, OF INDIANAPOLIS, INDIANA, ASSIGNOR OF ONE-HALF TO JOHN C. ERTEL, OF INDIANAPOLIS, INDIANA.

ELECTRIC TIME-SWITCH.

No. 807,017.

Specification of Letters Patent.

Patented Dec. 12, 1905.

Application filed June 5, 1905. Serial No. 263,821.

To all whom it may concern.

Be it known that I, MILTON T. CAMPBELL, a citizen of the United States, residing at Indianapolis, in the county of Marion and State 5 of Indiana, have invented certain new and useful Improvements in Time-Switches, of which the following is a specification.

The object of my invention is to produce a simple yet effective time-controlled means for 10 automatically closing and opening a lighting-circuit.

The accompanying drawings illustrate my invention.

Figure 1 is a plan of a clock-train provided 15 with an embodiment of my invention, the time-indicating dial, however, and the minute-hand being omitted. Fig. 2 is an elevation of the parts beneath the operating-disk, said disk being indicated in dotted lines. Fig. 3 is a central vertical section of the parts shown 20 in Fig. 2, the stationary cam, however, being shown in full lines. Fig. 4 is a perspective view of the inner face of the cam-carrying disk. Fig. 5 is a side elevation of some of 25 the parts shown in Fig. 3; Fig. 6, a front elevation on a small scale of said cam-carrying disk.

In the drawings, 10 indicates a standard twenty-four-hour time-train, the hour-sleeve 30 30 of which is mounted on the minute-shaft 9 and is rotated once in each twenty-four hours and carries the usual hour-hand 12, which is attached to the hour-sleeve 11 by the usual friction-sleeve. Frictionally mounted on the 35 sleeve 11 is a clutch member 13, which coacts with a clutch member 14, carried by the cam-carrying disk 15, sleeved upon the hour-sleeve 11, said clutch members consisting of intermeshing axial fingers, which will permit axial 40 movement of the disk 15 on the hour-sleeve, but will produce rotation of the disk with the hour-sleeve in any axial position of the disk.

Attached to the clock-frame is a stationary cam or snail 16, which terminates at a point 45 immediately above the axis of the hour-sleeve, the end being a greater distance from the frame than the beginning. Secured to the inner face of the disk 15 is an annular flange 20, the forward end of which is rounded so as to 50 gradually engage the snail 16 and the rear end of which is slightly undercut, as shown at 20', for a reason which will appear. Disk

15 is normally urged inward by means of a spring 21, which surrounds the hour-sleeve and lies between said disk and the hour-hand. 55

Secured to the clock-frame above the time-shafts and beneath the disk 15 is an insulating-plate 22, upon which are secured terminals 23 23 and 23' 23', which form parts of the two sides of a lighting-circuit. Pivoted 60 to the inner ends of the two terminals 23' are two swinging switch members 25 25, which are connected at their free ends by a suitable insulating-plate 26. The free ends of the two terminals 25 are normally urged outward 65 away from contact with the adjacent ends of the terminals 23 23 by means of a light spring 27, which is only sufficient to urge the swinging members outward and is considerably lighter than the spring 21. Pivoted to the 70 disk 15 coincident with the axis thereof is a yoke 30, which carries a cam-flange 31, and also pivoted upon the disk in the same manner is a second yoke 32, which carries a cam-flange 33, the flange 33 being slightly nearer 75 the center than the flange 31, so that the two flanges may be brought one within the other and adjusted relative to each other so as to change their effective length or so as to separate them to permit individual action at different times during the twenty-four hours. 80

It is often desirable that automatic lighting and extinguishing be accomplished at two different periods during the twenty-four hours, and in order to do this I provide a supplemental cam-flange 34, which may be adjusted at any desired point in an annular slot 35, formed in disk 15, this slot being so arranged that the cam 34 will coöperate with the snail 16. In order that the cam-flange 34 may be 90 withdrawn from active position when desired, I provide a radial recess 36, into which the shank 34' of the cam-flange 34 may be projected to thus withdraw cam 34 from alignment with the snail 16. The cam 34 is held 95 in any desired position by means of a thumb-nut 34".

In order to provide means by which the circuit may be closed independent of the time-train, I provide a cam 40, which is pivoted to 100 plate 22 adjacent the free ends of the swinging switch members 25, and said cam is provided with a suitable handle 41, by means of which it may be swung.

In operation suppose it be desired to close the lighting-circuit at six o'clock in the evening—*i. e.*, eighteen o'clock. The disk 15 will be turned upon the hour-sleeve until the number "18" lies immediately beneath the hour-hand no matter where it may be, the arrangement of the cam-flange 20 being such that its coacting end 20' will come to the end of the snail 16 when the mark "24" is uppermost. The mark "24" will always be uppermost whenever the hour-hand reaches the point on the time-dial (not shown) which corresponds to the hour indicated by that portion of the disk which lies immediately beneath the hour-hand—that is to say, if the number "4" of disk 15 lies beneath the hour-hand the hour-hand when it reaches number "4" on the time-dial will have brought the number "24" on the disk 15 to the highest point, and thereupon the spring 21 will urge disk 15 inward. If now the cam-flange 31 has been so set that it will also be in engagement with the plate 26 when the inward movement of the disk 15 is accomplished, the switch-arms 25 will be swung inward and brought into engagement with the terminals 23 23 to thus complete the circuit, and the circuit will remain closed until, as the disk 15 is advanced by the time-train, the end of the cam 31 is reached, whereupon spring 27 will throw the switch members outward. The length of period of lighting may be determined by properly setting the cam 34 angularly on the disk 15—that is, if the lighting period is to equal the hour length of the entire cam 31 it will be so set that its forward end will engage plate 26 just as the undercut end of 20' of the flange 20 reaches the end of the snail 16, while if a shorter period of lighting is desired the cam 31 will be advanced the required amount, so that it will engage the plate 26 or flange 20, the arrangement being such that the time of lighting will equal the number of hours indicated between the point "24" on the dial of disk 15 and that point on said dial to which the rear end of the cam 31 may be brought. If a longer period of lighting is desired, cam-flange 33 will be projected beyond either the forward or rear end of the cam 31, so as to thus give the cam-flange a greater effective length.

When it is desired to have two periods of lighting during the twenty-four hours, the flange 34 will be properly set in its groove 35, so as to be acted upon by the snail 16 in the same manner as said snail acts upon the flange 20, and the flange 33 will then be adjusted in proper correlative position to the flange 34 in a manner which will be readily understood. It will also be apparent from the description already given that if the flanges 31 and 33 be so adjusted with relation to the flanges 20 and 34 that they will not engage the switch members at a time when said flanges 34 and 20 are

not engaged by the snail there will be no closing of the circuit.

65

I claim as my invention—

1. The combination, with a time-train, of a cam-disk driven by the hour-sleeve thereof, intermediate connections between said disk and hour-sleeve permitting axial movement of the disk without preventing angular movement, means for automatically shifting said disk axially, switch mechanism, and means operated by the axial movement of the disk for operating said switch mechanism.

75

2. The combination, with a time-train, of a cam-disk driven thereby, a spring for normally urging said cam-disk axially in one direction, a cam-flange carried by said cam-disk, a snail arranged to coöperate with said cam-flange to shift said disk axially in opposition to the spring, a switch member arranged in conjunction with said cam-disk to be operated in one direction upon axial movement of the cam-disk in one direction, and means for moving the switch member in an opposite direction upon the opposite axial movement of the cam-disk.

80

3. The combination, with a time-train comprising an hour-sleeve, of a cam-disk journaled thereon, a driving connection between said cam-disk and hour-sleeve permitting angular and axial adjustment of the disk upon the hour-sleeve, a cam-flange carried by the cam-disk, a coacting stationary snail coacting with said cam-flange to shift the cam-disk axially in one direction, a spring serving to urge the cam-disk axially in the opposite direction, an angularly-adjustable cam-flange carried by said cam-disk, and a movable switch member arranged to be engaged by said angularly-adjustable cam-flange.

95

4. The combination, with a time-train comprising an hour-sleeve, of a cam-disk journaled thereon, a driving connection between said cam-disk and hour-sleeve permitting angular and axial adjustment of the disk upon the hour-sleeve, a cam-flange carried by the cam-disk, a coacting stationary snail coacting with said cam-flange to shift the cam-disk axially in one direction, an angularly-adjustable cam-flange carried by said cam-disk, and a movable switch member arranged to be engaged by said angularly-adjustable cam-flange, and a second angularly-adjustable switch-operating cam-flange also carried by a cam-disk.

105

5. The combination, with a time-train comprising an hour-sleeve, of a cam-disk journaled thereon, a driving connection between said cam-disk and hour-sleeve permitting angular and axial adjustment of the disk upon the hour-sleeve, a cam-flange carried by the cam-disk, a coacting stationary snail coacting with said cam-flange to shift the cam-disk axially in one direction, an angularly-adjustable cam-flange carried by said cam-disk, a movable

110

120

125

switch member arranged to be engaged by said angularly-adjustable cam-flange, a second angularly - adjustable switch - operating cam-flange also carried by a cam-disk, a second 5 snail-engaging cam-flange carried by the disk, and means for adjusting said second snail-engaging flange into and out of operating position.

In witness whereof I have hereunto set my hand and seal at Indianapolis, Indiana, this 3d ¹⁰ day of June, A. D. 1905.
